United States Patent Office

Des. 183,942
Patented Nov. 18, 1958

183,942

MAIL BOX

Charles A. Masso, Erie, Pa.

Application November 7, 1957, Serial No. 48,365

Term of patent 14 years

(Cl. D74—9)

FIG. 1

FIG. 2

FIG. 3

Fig. 1 is an isometric view of a mail box embodying my new design;

Fig. 2 is another isometric view thereof as it appears in closed position; and

Fig. 3 is a side elevational view thereof, the side opposite thereto being similar in appearance.

The back of the mail box is plain and unornamented.

I claim:

The ornamental design for a mail box, as shown and described.
